UNITED STATES PATENT OFFICE

2,692,319

CIRCUIT INTERRUPTER

Robert C. Dickinson and Russell E. Frink, Pittsburgh, Pa., assignors to Westinghouse Electric Corporation, East Pittsburgh, Pa., a corporation of Pennsylvania

Application May 26, 1951, Serial No. 228,446

7 Claims. (Cl. 200—147)

1

This invention relates to circuit interrupters in general, and, more particularly, to arc-extinguishing structures therefor.

In United States patent application Serial No. 720,165, filed January 4, 1947, now U. S. Patent 2,616,007, issued October 28, 1952, to Robert C. Dickinson and Russell E. Frink, entitled "Circuit Interrupter," and assigned to the assignee of the instant application, there is disclosed and claimed an air break-type of circuit interrupter utilizing a substantially H-shaped magnet, which is at a floating potential. This H-shaped magnet, when energized, serves to force two portions of the established arc upwardly into a pair of stacks of insulating plates. A transfer interrupting stack is utilized to interrupt the transfer arc which bridges the transfer arc horns associated with the H-shaped magnet.

One improvement which we have made over the circuit interrupter described in the aforesaid patent is in the arrangement for venting the arc gases from the transfer stack. In the aforesaid patent, venting of the arc gases was provided for by cutting windows in the side walls of the arc chute and letting the arc gases from the transfer stack vent laterally out of the arc chute. Our improved venting arrangement constitutes less of a hazard to personnel, and avoids the possibility of flash-over between adjacent poles, which are generally placed closely together.

It is a general object of our invention to improve the interrupting structure disclosed in the aforesaid patent.

It is a more specific object of our invention to provide an improved venting arrangement for the arc gases generated within the transfer interrupting stack.

It is a further object of our invention to so configure the side pole plates of the magnet as to cause the several portions of the established arc to rise up within the two stack assemblies at substantially the same rate of speed, so that more effective and efficient utilization is made of both stack assemblies simultaneously.

Still a further object is to provide an improved method of assembling the component parts of a circuit interrupter of the foregoing type so that manufacture and assembling operations may be rendered more economical and rapid.

Another object is to provide a means for preventing magnetic forces from changing the configuration of the blowout coils, and to do this in a simplified and effective manner.

Further objects and advantages will readily become apparent upon reading the following speci-

2

fication, taken in conjunction with the drawings, in which:

Figure 1 is a vertical sectional view through a circuit interrupter embodying our invention, the contact structure being shown in the closed circuit position;

Fig. 2 is a vertical sectional view taken along the line II—II of Fig. 1;

Fig. 3 is a vertical sectional view taken along the line III—III of Fig. 1;

Fig. 4 is a top plan view of our improved circuit interrupter;

Fig. 5 is an enlarged fragmentary plan view in section, taken generally along the line V—V of Fig. 1; and,

Fig. 6 is an enlarged elevational view of a transfer arc horn.

Referring to the drawings, and more particularly to Fig. 1 thereof, the reference numeral 1 generally designates an arc chute comprising a pair of serially related stacks of arc extinguishing plates 2, separated by a generally H-shaped magnet 3 disposed at a floating potential. A pair of serially related energizing coils 4, 5 serve, when energized, to set up a magnetic field within the magnet 3. Associated with the energizing coils 4, 5 are a pair of transfer arc horns 6, 7, the transfer arc between which is extinguished within a transfer interrupting stack, generally designated by the reference numeral 8, and more fully described hereinafter.

Contact structure 9 is provided to close the circuit through the interrupter. The contact structure 9 includes a relatively stationary contact 10, which may have a slight lateral motion to provide contact pressure, and a cooperating movable contact 11 positioned at the outer extremity of a rotatable contact arm 12, operated by any suitable mechanism, which forms no part of our invention. A line connection 13 may be made to the stationary contact structure 10, and the other line connection 14 may be made to the rotatable contact arm 12 in the manner indicated in Fig. 1.

Following operation of the contact opening mechanism the movable contact 11 moves leftwardly away from the stationary contact 10 to establish an arc therebetween. Because of the loop circuit including the substantially horizontal line connections 13, 14 and the movable contact arm 12, the established arc 15 drawn therebetween will tend to bow upwardly. Due to the proximity of the depending pole portions 16, the magnetic flux surrounding the established arc 15 will be distorted thereby. Thus, the flux above the arc 15 will pass through the depending pole portions

3

16 and through the yoke or centrally-disposed core 17 of the magnet 3. The magnetic flux below the arc 15 will merely pass through the air space. Consequently, since the flux below the arc 15 has a greater flux density than the flux density in the air above the arc 15 (the flux above the arc 15 having passed through the magnet structure 3), the arc 15 will be magnetically urged upwardly into contacting engagement with the transfer arc horns 6, 7.

We provide a plurality of spaced slotted ceramic plates 18 associated with the transfer interrupting stack 8, and more clearly disclosed in Figs. 1 and 2. With particular attention being directed to Fig. 2, it will be observed that each refractory plate 18 has a slot 19 provided therein, the upper closed end 20 of which is laterally displaced to one side of the center-line 21 of the plates. The plates 18 are assembled alternately, as shown in Fig. 2, with the closed ends 20 thereof of alternating about the center-line 21, that is, the closed end 20 of one plate being to one side of the center-line 21, and the closed ends 20 of the immediately adjacent plates 18 being disposed to the other side of the center-line 21. The resulting construction provides a zig-zag arc passage 22, as indicated in Fig. 2 of the drawings.

When the moving contact 11 has arrived at the position 11b in Fig. 1, the arc extending between it and the stationary contact 10 may consist of three portions, namely, 15a, 15b and 15c. The transfer arc portion 15b extends between the transfer arc horns 6, 7 and is extinguished within the transfer interrupting stack 8. This causes an energization of the two serially related blow-out coils 4, 5 surrounding the yoke or central core 17 of the H-shaped magnet 3, as shown more clearly in Fig. 2 of the drawings.

It will be observed that the depending pole portions 16 extend downwardly below the left-hand interrupting stack 2A, whereas there is no, or relatively little, pole plate portion below the right-hand extinguishing stack 2B. Thus, the transverse magnetic field just below the interrupting stack 2A is more intensified than the transverse magnetic field just below the interrupting stack 2B. The reason for this is that normally the arc portion 15c, which is closer to the interrupting stack 2B, tends to rise up within the stack 2B faster than the arc portion 15a, which is initially drawn farther away from the interrupting stack 2A. However, for most effective operation of the interrupter as a whole, it is desirable to have both arc portions 15a, 15c move upwardly at the same rate of speed within the extinguishing stacks 2A, 2B.

By the particular configuration of the depending pole plate portion 16, as shown in Fig. 1, the magnetic field is intensified just below the extinguishing stack 2A and thereby accelerates the upward travel of the arc portion 15a within the stack 2A so that its position and speed upwardly within the extinguishing stack 2A approximates that of the arc portion 15c upwardly within the extinguishing stack 2B.

Each extinguishing stack 2A, 2B includes a plurality of spaced ceramic or refractory plates 24, which more clearly are shown in Fig. 3. Each plate 24 has a closed slot 25 extending upwardly therein, the upper closed end 26 thereof being laterally displaced to one side of the center-line 27 of the plates 24. Preferably, the refractory plates 24 are spaced from each other by sections of asbestos rope 28, or narrow spac-

4

ing strips, and cemented thereto to form a unitary stack assembly, which may be bodily placed downwardly within the interrupter 1 and rested upon the upper ends 29 of a pair of ceramic arc shields 30. The arc shields 30 provide an entrance portion upwardly into the arc chute 1 and have lug portions 31 integrally formed therewith which extend through openings 32 provided in the insulating rectangularly-shaped arc-chute jacket 33, as more clearly shown in Figs. 2 and 3 of the drawings.

To prevent the gas pressure generated within the extinguishing stacks 2A, 2B from blowing the stacks 2A, 2B completely upwardly out of the arc chute 1, retainer strips 34 are provided within the arc chute jacket 33 at the upper end thereof, as indicated in Fig. 4 of the drawings. Preferably, bolts 35 are utilized to maintain the retainer strips in position.

The transfer arc horns 6, 7 are of identical construction, and Fig. 6 indicates an enlarged side-elevational view of one of them, say transfer arc horn 6. It will be observed that the lower end is curved around, as at 36, to form an arc horn for the transfer stack 8. The upper portion 37 of the arc horn 6 serves as an arc horn for interrupting stack 2A. Likewise, the transfer arc horn 7 has an upper portion thereof 38, which serves as an arc horn for the interrupting stack 2B. Cooperating with the stationary contact 10 and connected thereto by a strap connector 39 is an arc horn 40. Disposed above the arc horn 40 is a barrier plate 41 which, as is the case with the arc horn 40, is suitably secured to a pair of insulating plates 42 by suitable means, not shown.

Similarly, disposed at the outer end of the circuit interrupter 1 is an arc horn 43, above which is a barrier plate 44 secured by suitable means, not shown, to a pair of plates 45. Spacer strips 23 space the stacks 2A, 2B away from the arc horns 40, 43.

Each transfer arc horn 6, 7 has a laterally extending lug portion 46 (Fig. 6) which extends through a slot 47 provided in each side wall of the insulating arc chute jacket 33. Also, each transfer arc horn 6, 7 has connected therewith a lug portion 48 which serves, as shown in Fig. 5, to laterally space insulating rectangularly-shaped washers 49 surrounding the yoke or core 17. A washer 49 is disposed immediately adjacent each blow-out coil 4, 5. Thus, it will be evident that there is provided within our improved arc chute 1 a pair of venting passages 50 (Fig. 5), each of which is defined by a pair of the washers 49, the yoke 17 and the inner side of a transfer arc horn 6, 7. There results a distinct advantage inasmuch as there is a ready means of escape-ment of the arc gases generated within the transfer interrupting stack 8.

In the aforesaid patent, such gases were forced to move laterally out of windows provided in the side walls of the arc-chute jacket. In our present improved construction, these gases are readily transmitted upwardly through the pairs of venting passages 50, and upwardly out of the arc chute 1.

It will be observed that not only are the washers 49 maintained laterally apart against the magnetic forces exerted by energizing the blow-out coils 4, 5 by the lugs 48 associated with the transfer arc horns 6, 7 but also the upper notched ends 51 of the plates 18 of the transfer interrupting stack 8 serve to maintain the washers 49 apart, as more clearly shown in Fig. 2.

The plates 18 are inserted into slots 52 provided in the upper ends of the arc shields 30. The two coils 4, 5 are electrically connected together at the upper ends thereof by the terminal leads 53, 54 and a connecting bolt 61. Consequently, both coils 4, 5 are in series electrically between the transfer arc horns 6, 7.

The operation of our improved interrupting device is as follows: The movable contact 11 first moves toward the left, as viewed in Fig. 1, to the position 11a. The arc 15 is established between it and the stationary contact 10. The arc 15 is affected by the depending pole plate portions 16 of the magnet 3, and moves upwardly into engagement with the transfer arc horns 6, 7. Meanwhile, the movable contact 11 moves to the position 11b. The arc then consists of three portions 15a, 15b and 15c indicated in Fig. 1. The arc portion 15b is interrupted within the transfer interrupting stack 8, thereby energizing the serially related blow-out coils 4, 5, and providing a transverse magnetic field across the pole plates 55, said magnetic field being particularly intensive, due to the configuration of the plate portion 16, within the left-hand arc-extinguishing stack 2A.

The left-hand end of the arc portion 15a transfers to the arc horn 43, and the right-hand end of the arc portion 15c transfers to the right-hand arc horn 40. The two arc portions within the respective extinguishing stacks 2A, 2B may then be respectively designated by the reference characters 56, 57, as indicated in Fig. 1. Each arc portion 56, 57 rises upwardly within the stacks 2A, 2B at substantially the same rate of speed, and is forced upwardly within the zig-zag arc passages 58 provided by the several plates 24 provided in the extinguishing stacks 2A, 2B. These arc portions 56, 57 are quickly extinguished at the upper ends 26 of the slots 25 provided in the plates 24, and the circuit through the interrupter 1 is broken.

Preferably, to prevent the transfer arc horns 6, 7 from being shorted by the pole plates 55, and thereby shorting out the serially related blow-out coils 4, 5, we provide an insulating fish paper strip 59 between each pole plate 55, and the side of the arc chute jacket 33. Each insulating plate 59 has a slot 59a provided therethrough (Fig. 5) to accommodate the yoke 17, so that the latter may abut against the side of the pole plates 55. These fish paper strips 59 merely have to provide insulation between the pole plates 55 and the transfer arc horns 6, 7 sufficient to withstand the reactance voltage of the blow-out coils 4, 5 in series. Since this is a small voltage, the insulation provided by such strips 59 is sufficient.

To maintain the pole plates 55 rigidly in position, a pair of bolts 60 extend completely through the arc chute 1 immediately inside of the inner bends of the blow-out coils 4, 5, as indicated in Figs. 1 and 2 of the drawings.

To assemble the arc chute, the arc shields 30 are first put into position. Then follows the insertion of the transfer arc plates 18 within the slots 52. Then follows the transfer arc horns 6, 7, the blow-out coils 4, 5 with the side walls of the arc chute jacket 33 pressed outwardly sufficiently far to enable the lug portions 46 of the transfer arc horns 6, 7 to be forced through the slots 47 of the arc chute jacket 33. The yoke 17 may then be placed in position, and then the extinguishing stacks 2A, 2B, together with the arc horns 40, 43.

Then follows the insulating strips 59, and lastly, the side pole plates 55. The bolts 60 may then be inserted to rigidly hold the assembly in position.

It will be observed that the transfer arc horns 6, 7 effectively shield any passage of the gases generated within the transfer stack 8 from passing through the extinguishing stacks 2A, 2B. This feature is very important for the proper functioning of the interrupter. Also, by the proper configuration and disposition of the depending pole plate portions 16 of the pole plates 55, we have provided a substantially equal upward velocity of travel of the arc portions 56, 57 within the respective extinguishing stacks 2A, 2B. By the provision of the venting passages 50, the operation of the transfer interrupting stack 8 is rendered more effective. The absence of a satisfactory method of disposing of the exhaust gases from the transfer stack was a decided limitation in the interrupting device disclosed in the aforesaid patent. Also, the present construction renders the device more economical to manufacture and easier to assemble. By utilizing an H-shaped magnetic circuit, there is a reduction in the weight of the iron.

Although we have disclosed a particular structure, it is to be clearly understood that the same was merely for the purpose of illustration, and that changes and modifications may readily be made therein by those skilled in the art, without departing from the spirit and scope of the appended claims.

We claim as our invention:

1. A circuit interrupter including contact structure having a relatively stationary contact and a co-operable movable contact, the movable contact being separable from the relatively stationary contact to establish an arc, a substantially H-shaped magnet assembly including a pair of magnetic pole plates and an interconnecting core, a pair of extinguishing structures on opposite sides of the core, one disposed immediately adjacent the relatively stationary contact and the other more remote therefrom, means for subdividing the initially formed arc into two serially related arc portions, one arc portion moving into one extinguishing structure and the other arc portion moving into the other extinguishing structure, and the magnet assembly having depending pole plate portions associated with the more remote extinguishing structure so that the arc portions will move within the two extinguishing structures at substantially the same rate of speed.

2. A circuit interrupter including a substantially H-shaped magnet assembly having a yoke portion, a pair of extinguishing structures disposed on opposite sides of the yoke portion, a blowout winding about the yoke portion, a pair of transfer arc horns connected to the blowout winding, a transfer arc interrupting device, means for establishing an arc, and means providing one or more venting passages between the extinguishing structures extending along the yoke portion freely venting the arc gases from the transfer arc interrupting device to the ambient region exterior of the circuit interrupter.

3. A circuit interrupter including a substantially H-shaped magnet assembly having a yoke portion, a pair of extinguishing structures disposed on opposite sides of the yoke portion, a pair of blowout windings about the yoke portion, a pair of transfer arc horns connected to the blowout windings, a transfer arc interrupting de-

vice, means for establishing an arc, means for spacing the blowout windings laterally apart, and the space between the blowout windings forming a pair of venting passages on opposite sides of the yoke portion extending along the yoke portion from the transfer arc interrupting device to the region exterior of the circuit interrupter.

4. A circuit interrupter including an arc chute having an insulating casing, a pair of openings in the side walls of the casing, a substantially H-shaped magnet assembly having a yoke portion, a pair of extinguishing structures disposed on opposite sides of the yoke portion, a pair of blowout windings about the yoke portion, a pair of transfer arc horns having lug portions extending through the side openings in the casing and connected to the blowout windings, a transfer arc interrupting device, means for establishing an arc, means including the transfer arc horns for spacing the blowout windings laterally apart, and the space between the blowout windings forming a pair of venting passages on opposite sides of the yoke portion extending along the yoke portion from the transfer arc interrupting device to the region exterior of the circuit interrupter.

5. A circuit interrupter including contact structure having a relatively stationary contact and a cooperable movable contact, the movable contact being separable from the relatively stationary contact to establish an arc, a substantially H-shaped magnet assembly, a pair of extinguishing structures, one extinguishing structure being disposed immediately adjacent the relatively stationary contact and the other disposed more remote therefrom, and the magnet assembly having asymmetrically depending pole plate portions providing the magnetic circuit with a lower reluctance adjacent the entrance to the extinguishing structure more remote from the relatively stationary contact than the entrance to said one extinguishing structure.

6. A circuit interrupter including a substantially H-shaped magnet assembly having a yoke portion, a pair of extinguishing structures disposed on opposite sides of the yoke portion, a blowout winding about the yoke portion, a pair of transfer arc horns connected to the blowout

5

winding, a transfer arc interrupting device at one end of the pair of arc extinguishing structures, each of said arc extinguishing structures being vented at the other end thereof, means for establishing an arc adjacent the transfer arc interrupting device, and a venting passage extending between the pair of arc extinguishing structures along the yoke portion freely venting the arc gases from the transfer arc interrupting device to the ambient region externally of the interrupter adjacent the other end of the pair of arc extinguishing structures.

10

7. A circuit interrupter including a substantially H-shaped magnet assembly having a yoke portion, a pair of extinguishing structures disposed on opposite sides of the yoke portion, each of said arc extinguishing structures comprising a plurality of plate-like portions of insulating material having spaces therebetween through which arc gases may pass, said yoke portion having a height several times its thickness with its height extending in the same direction as the greatest dimension of plate-like portions, an elongated blowout winding about the yoke portion, means for establishing an arc adjacent one end of the pair of arc extinguishing structures, and a venting passage extending between the pair of arc extinguishing structures along the yoke portion in the direction of its height and extending from the end of the pair of arc extinguishing structures at which the arc is established to the other end thereof.
